UNITED STATES PATENT OFFICE

STEPHEN SIMPSON, OF EXMOUTH, ERNEST WILLIAM SMITH, OF LONDON, AND SANDFORD ROBINSON, OF LIVERPOOL, ENGLAND, ASSIGNORS TO UNITED GAS INDUSTRIES LIMITED, OF LONDON, ENGLAND

GAS AND SIMILAR METER

Application filed February 7, 1931, Serial No. 514,228, and in Great Britain February 12, 1930.

This invention relates to pre-payment mechanism of gas and similar meters, and is especially applicable to mechanism the subject-matter of the British prior Patents Nos. 5 288,367 and 292,705. Thus the invention relates to coin mechanism adapted for use with coins of different values such as one shilling and one penny, and it has among its objects to secure a slower speed of the spindle which 10 projects from the upper gas or valve chamber of the meter, to provide simple means adapted by a single adjustment to render the mechanism operable in the use of the intended coin and to effect the corresponding change 15 in the quantity of gas to be supplied according to the value of the coin intended to be used and generally to improve the construction and operation of pre-payment mechanism of gas and similar meters that are 20 adapted for use with coins of different values.

According to the invention the coin holder is provided with means comprising a stop plate, stop lever or the equivalent, which upon being set into a position for the reception 25 of the coin of higher value (or of a lower value) and the coin holder restored to its position within its casing, causes a change of gear between the operating spindle deriving movement from the meter, and a measuring 30 screw formed as an externally screw-threaded sleeve or its equivalent that is adapted to have imparted to it a rectilinear movement to open or to close the valve, the movement to open the valve being effected on 35 the operation of the coin holder on the insertion of a coin, while the movement to close the valve is effected on the operation of the meter in the consequent movement of the measuring screw or its equivalent.

40 According to the invention moreover the measuring screw or its equivalent is adapted for the reception of a splined, square or other spindle that is free to move axially to cause the change of gear, and the spindle is set concentrically with, and is adapted to protrude at one end into, the coin holder casing, and the measuring wheel mounted within the casing is adapted to rotate with the spindle. Thus upon the stop plate, stop lever or the 45 equivalent provided upon the coin holder,

being set into operative position it may engage with the inwardly protruding end of the axially movable spindle, on the introduction of the coin holder into its casing, and thus may effect the change of gear in the 55 axial movement of the spindle: while if the stop plate, stop lever or the equivalent be retracted so as to be inoperative, the mechanism on the rotation of the coin holder, operates through the normal gear and causes a 60 supply of gas corresponding for example to an inserted coin of lower value.

According to the invention moreover the measuring screw or its equivalent passes 65 within a surrounding rotatable and internally screw-threaded sleeve, adapted to be held from axial movement, and having mounted thereon so as to rotate therewith, a sliding sleeve whereby the sliding sleeve has imparted to it the rotation of the internally 70 screw-threaded sleeve. Means are provided within the internally screw-threaded sleeve and connected by or comprising such means as a transversely disposed pin passing through oppositely disposed longitudinal 75 slots in the internally screw-threaded sleeve, by which the end of the axially movable spindle may cause the axial movement of the sliding sleeve upon contact with it of the stop plate or its equivalent on the insertion of the 80 coin holder into its casing. By such means the sliding sleeve on the insertion of the coin holder into its casing is adapted to have a movement imparted to it to bring a worm wheel or other gear wheel carried by it, or 85 integrally formed upon it, from engagement with one worm or gear wheel into engagement with another, the respective gear ratios in the respective positions of the sliding sleeve being determined according to the respective coin 90 values and the respective quantities of gas to be supplied, determined according to those values.

The invention comprises the features hereinafter described.

The invention is illustrated by way of example in the accompanying drawings, in which

Figure 1 is a plan view partly in section of the pre-payment mechanism provided ac- 100

cording to the invention, in which the mechanism is indicated in the position of the respective parts for operation by a coin of lower value, such as a penny.

5 Figure 2 illustrates a detail view of the coin holder withdrawn from the coin holder casing, together with the parts upon which it is mounted, the coin holder being set for operation by a coin of lower value.

10 Figure 3 is a side elevation corresponding to Figure 2.

Figures 4, 5 and 6 are views similar to Figures 1, 2 and 3 in which the respective parts are shown in the position for operation 15 by a coin of a higher value, such as a shilling.

Figure 7 is a rear sectional view on the line B—B, Figure 1.

Figure 8 is a rear sectional view on the line A—A, Figure 1.

20 Figure 9 is a front view corresponding to Figure 1.

Figure 10 is a detail side elevation taken from the inner side of the coin holder, in which the parts are indicated in the positions corresponding to that for operation by 25 a coin of higher value, and

Figure 11 is a transverse sectional view through the coin holder in the position of the parts set for operation by a coin of 30 lower value.

In carrying the invention into effect according to one construction that is illustrated in the accompanying drawings, the coin holder *a* is mounted upon the inner 35 face of a disc *b* in a position normal to its face, and the disc *b* carrying the coin holder is mounted to rotate concentrically upon and in contact with the front plate *c* of the coin holder casing *d*, the front plate *c* being applied at the front of the said casing as in the 40 construction of the prior patents aforesaid, the edges of the front plate *c* being suitably notched at *c*¹ and calibrated in well-known manner to permit of its adjustment with respect to a pin *d*¹ (Figure 9) mounted upon the flange *d*⁶ of the casing *d*, to vary the angle through which the coin holder moves, and thus to determine the amount of gas to be supplied to the value of the respective 45 coins that may be used.

The front plate *c* may be secured in its position at the front of the casing *d* in an annular recessed part of the flange *d*⁶ prepared for its reception, and may be retained 55 in that position by means of a retaining ring *t* which in the illustrated construction has a curved rearwardly extending lug *t*¹ (Figure 9) which enters a recess *t*² in the front wall in diametrically opposite position to that of the pin *d*¹, while an extension *t*³ may be provided upon the ring *t* in a diametrically opposite position to that of the lug *t*¹, and may be adapted to be held in position by means such as a rotatable catch *t*⁴ which 60 may be held and locked in position for ex-

ample by engagement of the hasp of the coin holder door, or otherwise, it being however understood that the retaining ring *t* or the equivalent may be secured or locked in position in any usual or convenient manner, whereby it is only adapted to be unfastened by an authorized person or for adjusting the coin holder to render the mechanism operable with a coin of a higher or lower value. It will be understood that the inner peripheral edge of the retaining ring *t* may be recessed at *t*⁵ for the accommodation of the pin *d*¹.

The disc *b* may advantageously be provided of a dish-shape to contact at the face 30 of its peripheral flange *b*¹ with the inner face of the flat front plate *c*; and the disc *b* is mounted upon a pin by which the disc may be rotated by means of a radially disposed handle *b*². The handle *b*² may be so mounted upon the pin and beneath its external head *b*³ that it has a lost movement in known manner through a small arc of a circle, and the pin is provided with an internal head *b*⁴ between which and the adjacent face of the 35 disc *b*, a bifurcated spring plate *b*⁵ (bent transversely at its bifurcated part) is inserted so that its bifurcated part strides the pin and imposes pressure in a central position upon the disc, so that its peripheral 40 flange *b*¹ is pressed against the inner face of the front plate *c*, the spring plate *b*⁵ being conveniently held in its set position by such means as a protruding part on the plate entering a hole set in determined position on the disc. A coin slot *b*⁶ (Figure 1) is provided in determined position in the disc *b* and a corresponding slot *c*⁶ is provided in the front plate *c* so that on a peripheral projecting part *b*⁷ (Figure 2) on the disc *b* being brought by the handle *b*² into position against a fixed stop *c*² provided on the rear face of the front plate *c*, the respective slots *b*⁶, *c*⁶ will as illustrated in Figures 1 and 9 come into coincidence for the insertion of the coin, and on the insertion of a coin, the coin holder *a* may be rotated for example in a clockwise direction viewed from in front of the coin holder casing.

In the coincident positions of the slots *b*⁶ and *c*⁶ (Figures 1 and 9) the handle *b*² will take the position indicated in Figure 9, so that after the coin has been inserted the handle is rotatable without communicating its movement to the disc *b* by reason of the handle being mounted in the manner hereinbefore described. Thus the coin slot *c*⁶ is covered before the movement of the handle *b*² becomes effective in the rotation of the disc *b*. By such means the coin slot *c*⁶ must necessarily be closed before engagement of the measuring wheel.

The coin holder *a* is advantageously disposed in a position beside the axis of the carrying disc *b*, and may have a U-shaped 130

transverse cross-section, and a cavity open at the respective ends of the holder adapted for the accommodation of a lengthwise sliding pawl plate *e*, by means of which engagement 5 is made with the measuring wheel *f*, and for the accommodation at its upper part of the operating coin. The upper part of the cavity is accessible to the coin through the slot *b*⁸ in the disc *b*, which otherwise serves 10 to form one end wall of the coin holder. The coin holder *a* may be constructed of two parallel plates 1 and 2 secured to the disc by outwardly extending lugs *a*² riveted to the disc *b* or otherwise secured as by soldering, 15 while the outer end wall may be formed by a part *a*³ of the plate 2 being bent into a transverse position with respect to the main part of the plate, and by the edge of the plate 1 being secured to it, as for example 20 by rectangular holes being provided in the part *a*³ of the plate 2 adapted for the reception of corresponding rectangular tenon-like projections *a*⁴ provided at the front edge of the plate 1.

25 The sliding pawl plate *e* is advantageously disposed to slide in contact with the outer plate 2 of the coin holder and any convenient means may be provided for the purpose. Thus at its lower end the plate *e* may be provided of a thickness corresponding to that of the lower part of the cavity in the coin holder, or the plate *e* may have integral projecting parts *e*⁸ (Figure 11) at its lower end and at each side, bent outwardly into position adjacent the inner wall or plate 1 of the coin holder. At the upper end the sliding pawl plate *e* is provided with an outwardly extending part *e*¹ that is adapted to be accommodated and to slide within a notch or open slot or corresponding form in the upper part of the end wall *a*³ of the coin holder adjacent the outer wall 2. By such means the part *e*¹ of the pawl plate *e* is guided in the notch or open slot, while at its upper end the part *e*¹ has an outward extension or tooth *e*² having an angular lower edge adapted to engage between the teeth of the measuring wheel *f*. The sliding pawl plate *e* is provided near its lower end with an outwardly protruding pin *e*³ which extends through a vertical slot *a*⁵ in the plate or wall 1 of the coin holder, and is provided for the reception of the lower end of a helical spring *e*⁴, the opposite end of which is secured to another pin *e*⁶ mounted at the upper end of the plate or wall 1 of the coin holder, in line parallel with the line of movement of the sliding pawl plate *e*, so that thus the latter is always subject to the action of the spring *e*⁴ and tends 120 always to maintain the outermost position permitted to it by the slot *a*⁵. The sliding pawl plate *e* is provided at or about the middle of its length with an aperture *e*⁵ through which the upper inwardly protruding flange *g*¹ of the adjusting plate *g* extends that is

125 mounted upon the outer face of the wall 2 of the coin holder, the flange *g*¹ extending into the coincident slots *a*⁷ provided respectively in the inner plates 1 and 2 of the coin holder, which are also coincident with the slot *e*⁵ in the plate *e* except that as illustrated in Figures 10 and 11 the slots *a*⁷ may extend below the slot *e*⁵. Thus the flange *g*¹ of the adjusting plate *g* extends across the cavity in the coin holder and is thus adapted to serve 130 for the support of the inserted coin.

135 The pin *e*³ extends through the plate *e* and serves at its reduced opposite end for mounting the adjusting plate *g*. For this purpose a vertical slot *g*² is provided in the adjusting plate *g*, and a helical spring *g*³ is mounted upon the reduced outwardly extending screw-threaded end of the pin *e*³ and is held in position by screw-threaded nut *g*⁴. At the lower end, the adjusting plate *g* is provided with a flange *g*⁵, that is adapted to engage within one of two transversely disposed slots *e*⁶, *e*⁷ at the lower end of the pawl plate *e*, and the adjusting plate *g* is adapted to be held within one or other of the slots *e*⁶ or *e*⁷ by the pressure of the helical spring *g*³. The outer wall 2 of the coin holder is at the lower end provided with an aperture *a*⁸, by which the flange *g*⁵ of the adjusting plate is accessible for engagement with either of the slots *e*⁶ or *e*⁷, the aperture *a*⁸ in the outer wall of the coin holder in common with the apertures *a*⁷ on the inner wall and outer walls permit in the lower position of the adjusting plate *g* the movement of the tooth *e*² 140 of the sliding pawl plate *e* as it moves inwardly to engage the measuring wheel *f* in the manner hereinafter described.

145 The adjusting plate *g* is provided at the upper and lower ends on the outer side with oppositely disposed outwardly inclined lugs *g*⁶, *g*⁷, by which the lower end of the adjusting plate may be raised for withdrawing the flange *g*⁵ from one or other of the slots *e*⁶, *e*⁷, for the purpose of adjusting the coin holder 150 for operation with coins of different value. This operation may be conveniently performed by the engagement of the lower lug *g*⁷ with the thumb and the upper lug *g*⁶ with the forefinger. The lower end of the adjusting plate *g* is thus raised by which the lower flange *g*⁵ may be withdrawn from one of the slots *e*⁶ or *e*⁷ whereby the plate *g* may then be moved upon the pin *e*³, and the plate set 155 so that the lower flange *g*⁵ may be engaged in the other of the slots, this movement being permitted to the plate *g* while its upper flange *g*¹ is adapted to be moved within the aperture *e*⁵ in the plate *e* and in the apertures *a*⁷ in the inner and outer walls 1 and 2 of the coin holder. The rectilinear movement of the adjusting plate may be facilitated by the provision of an outstanding flange *a*⁹ upon the inner edge of the aperture *a*⁸ in the outer wall 2 of the coin holder. A central vertical slot is 160

provided to extend from the aperture a^7 to the aperture a^8 in the plate or wall 2 of the coin holder, for the accommodation of the reduced end of the pin e^3 in its movement on the 5 adjustment of the plate e .

Means are provided to effect the change of gear in the manner hereinbefore described on the movement of the adjusting plate g into the second or upper position of the adjusting 10 plate, corresponding to that for a coin of a higher value, such as a shilling. Such means may consist of a stop plate or lever h which may be brought into position on the adjusting plate being brought into its effective position, 15 whereby on the introduction of the coin holder into the casing d the necessary change of gear is automatically effected. Thus the stop plate may be provided as a lever h or the equivalent, that may be brought into operative 20 position by actuation from the adjusting plate g as it assumes its second or upper position. In the illustrated construction the end wall a^9 of the coin holder is extended forwardly at a^{10} and in this extension a circular 25 hole a^{11} (Figure 5) is provided, concentric with the axis upon which the coin holder a and the disc b rotate, and of such diameter as to permit entry of the end of an axially movable spindle i by which the movement of the 30 measuring wheel f is transmitted to the valve operating mechanism of the meter. The inner plate 1 of the coin holder is provided with an outstanding inward extension a^{12} of the same shape as the extension a^{10} and with a 35 similar circular and concentric hole a^{11} therein, and set in position and adjacent to the extension a^{10} , with an interstitial space in which the stop plate or lever h is mounted upon a pin h^1 carried upon a lower part of the end 40 wall a^9 beneath the extension a^{10} , but disposed in line with the extension a^{12} of the inner plate 1 of the coin holder. The stop plate or lever h is so shaped and mounted that in the first or lowermost position of the adjusting 45 plate g (Figure 2), the holes a^{11} are open, and a rearwardly extending part h^2 is provided which engages within a lateral recess g^8 formed at the edge of the adjusting plate g , and a notch h^3 that is adapted to engage in 50 the upper edge of the recess g^8 when the adjusting plate is in the lower position indicated in Figure 2 and the pawl plate e is moved to engage the measuring wheel f . By such means in order to set the coin holder for 55 operation by a coin of a value such as a penny or a shilling, it is only necessary to raise the lower end of the adjusting plate in the manner hereinbefore described and to set it into its upper or lower position, whereby if in its 60 upper position for operation of a coin of the higher value, the holes a^{11} are obturated by the stop plate or lever h , and thus on the introduction of the coin holder so adjusted, into the casing, the spindle i will be moved axially 65 to a determined extent into the position indi-

cated in Figure 4, or if the coin holder be set for operation of a coin of lower value, the spindle i will not be moved (as illustrated in Figure 1) but will be permitted to pass through the open holes a^{11} .

The casing d in which the coin holder a is mounted has its integral rear wall adapted for mounting the measuring wheel f on the inside of the casing. The measuring wheel f may be integrally provided with a rearwardly extending boss f^1 , having an external annular groove and a circular flange exposed at the rear face of the casing d . The rear wall of the casing may be re-inforced by a plate d^2 , and a bifurcated plate d^3 bent transversely to the bifurcated part, may be adapted to straddle the boss f^1 at the position of the annular groove and to engage beneath the external head of the boss as a means securely to hold the boss f^1 of the measuring wheel 85 against axial displacement. The boss f^1 has a bore of a square or other cross-section according to the cross-sectional shape of the axially movable spindle i that is adapted to extend through. The measuring screw j and gear may be carried upon an outwardly extending frame d^3 supported from the rear wall of the casing d , the measuring screw j being mounted in alignment with the axis of the coin holder a . For this purpose the carrying frame d^3 may be set asymmetrically in order that the vertically disposed spindle i^1 may be conveniently accommodated with the worm wheel r and worm s mounted upon it at a position beside the respective parts 95 of the gear that are disposed coaxially with the axially movable spindle i to which movement is communicated from the measuring wheel f . The frame d^3 may consist of two parallel disposed longitudinal members secured at one end to the rear wall of the casing d , and at the other end being connected together by a transverse member d^4 through which the reduced end k^1 of an axially immovable sleeve k is carried, while in a middle 100 position a transverse wall d^5 is provided serving to support the opposite end of the axially immovable sleeve k . The axially immovable sleeve k is provided of tubular form and for the main part of its length is provided with an internal screw-thread corresponding to the external screw-thread provided upon the measuring screw j , it being understood that the measuring screw j has on its inner end a grooved collar l adapted 110 to engage a lever by means of which the meter valve is operated in known manner. The measuring screw j is also of tubular form and has its bore or part thereof of a transverse cross-section corresponding to the axially movable spindle i which passes through it. Thus the measuring screw j is adapted to move into and out of the axially immovable sleeve k in the operation of the gear.

Near the outer end, the axially immovable 120

sleeve h is provided with two longitudinal slots h^2 in opposite positions and parallel with its axis, through which slots may pass a pin m^1 transversely set, that engages the end 5 of the outer rotating sliding sleeve m . Thus the pin m^1 may serve as an abutment for the outer end of the axially movable central spindle i , (and the spindle i may be provided with a head i^1 by means of which its 10 complete withdrawal through the boss f^1 of the measuring wheel may be prevented), whereby on the adjusting plate g of the coin holder b being set for the use of a coin of a higher value such as a shilling, the axially 15 movable spindle i is forced to move against the transversely disposed pin m^1 , and to cause the axial movement of the rotating sliding sleeve m from one extreme position indicated in Figure 1 to the other indicated in Figure 20 4; this movement being effected for example against the resistance of a helical spring k^3 mounted within the outer end of the axially immovable sleeve h ; it being understood that the extent of movement of the axially mov- 25 able spindle i and the rotating sliding sleeve m is equivalent to that of the transversely disposed pin m^1 within its respective slots h^2 in the axially immovable sleeve h .

The carrying frame d^3 at a position beyond 30 the intermediate transverse wall d^5 may be provided for the support of the spindle n to which movement is communicated in usual manner from the meter. The spindle n is provided with two worms o, p in adjacent 35 positions, one worm o engaging a worm wheel q provided beneath and upon the inner end of the rotating sliding sleeve m , while the second worm p engages a worm wheel r mounted upon the upper end of a vertically 40 disposed spindle r^1 that may be suitably supported from the adjacent longitudinal member of the frame d^3 . A worm s is mounted upon the spindle r^1 and is set in such position that the worm wheel q provided upon 45 the rotating sliding sleeve m may engage with the worm s on the sleeve m being moved into its outermost position (Figure 4) corresponding to the adjustment of the coin holder for the use of a coin of higher value, 50 such as a shilling; so that by such means the movement imparted from the meter may in the second position of the rotating sliding sleeve m be considerably reduced by the interposition of the second worm p and worm 55 wheel r , the respective gear ratios being determined according to the respective coin values and the amount of gas to be supplied in the use of coins of those values.

It will be understood that on the insertion 60 of a coin through the coin slots c^x, b^x into the coin holder a and on the rotation of the handle b^2 in the clockwise direction, the sliding pawl plate e is depressed so that the tooth e^2 engages in one of the interstitial 65 spaces of the teeth of the measuring wheel f ,

by reason of the fact that the coin is of larger diameter than the depth of the flange g^1 which forms the bottom of the coin space in the coin holder. Thus on the coin being introduced, the flange g^1 is depressed against 70 the resistance of the helical spring e^4 , with the consequent engagement of the measuring wheel f by the tooth e^2 , whereby the upper edge of the coin protruding beyond the upper edge of the coin holder is pressed into contact with the internal periphery of the casing d . The casing d is provided on its internal periphery with a series of equidistant and parallel recesses d^7 (Figures 1 and 2) of a saw-toothed section, whereby in the rotation of the coin holder in a clockwise direction, the protruding edge of the coin slides over the recesses d^7 , so that on any attempt being made to reverse the movement of the coin holder, the outer edge of the coin 80 would engage against the short or substantially radial face of one of the recesses d^7 and thus the return of the coin holder would be prevented until it completes its clockwise travel into a position opposite the coin discharge slot or opening d^8 provided in the lower part of the casing d , adjacent the stop d^9 , which thus arrests the coin holder at the position of discharge through the said slot or opening, whereupon as the coin holder in 85 this position is inverted the coin falls into the coin receptacle, and the coin holder may then be returned by a reverse movement into its initial position with the coin slots c^x and b^x in coincidence.

It will be understood that the illustrated mechanism may be designed for the successive use of a limited number of coins, that is to say for example to the limit of 200 cubic feet of gas in the use of penny coins, and of 2,400 cubic feet of gas in the use of shilling coins. Thus on a number of coins being successively used in the manner described up to the limit of the mechanism, means may be employed to prevent any further operation of the mechanism. Such means may consist of a lever u (Figures 7 and 8) having at its lower end a transversely extending part u^1 , that is adapted to move up into a position completely to close the coin discharge slot d^8 . The lever u is advantageously mounted upon a spindle u^2 , and one of the ends of the spindle may conveniently be carried within a hole or bearing provided for its reception in the end wall of the casing d , while the opposite end may be supported by a pin u^3 on the transverse wall d^5 of the supporting frame. The upper end of the lever u may be diverted rearwardly at u^4 , in a line parallel with the axis of the spindle i and of the measuring screw j , and the diverted part u^4 may be provided with an inclined edge u^5 whereby under the weight of the lower part of the lever u , the part u^4 maintains contact with the rear peripheral edge of the grooved 100 105 110 115 120 125 130

collar l of the measuring screw, so that thus on the successive rotation of the measuring screw j on the insertion of a number of coins, the grooved collar l in moving rearwardly 5 towards the casing d will cause the part u^4 of the lever u to be moved outwards whereby the transversely extending part u^1 of the lever will come to lie immediately beneath the coin discharge slot d^8 . Thus as the measuring screw again moves forward on the gas 10 being consumed, the transverse part u^1 of the lever moves from under the coin discharge slot d^8 . In this way the coin holder after 15 successive operation with a determined number of coins is rendered inoperable until the gas paid for is consumed, and the lever u moves so that its transversely extending part u^1 passes from beneath the coin discharge slot d^8 .

20 An indicator may advantageously be provided which may be supported by the transverse part u^1 of the lever, and this may take the form of a rod v , which extends upwardly and across the casing d in the position indicated in Figures 7 and 8, so that the end of the rod may be diverted upwardly as an indicating finger v^1 within the casing v^3 , against a calibrated scale v^2 , the upper part of the scale being denoted in volume of gas 25 in return for coins of the higher value, and the lower part of the scale in volume of gas in return for coins of a lower value. Thus the indicating finger v^1 indicates to the consumer the amount of gas available for consumption on the operation of the pre-payment mechanism in return for a determined 30 number of coins of higher or lower value up to the limits in capacity of the mechanism, and the amount of gas that remains available for consumption at any moment in the 35 consumption of the gas paid for.

40 It will thus be understood that the mechanism is adapted to be set for operation by the use of coins of two different values merely by the adjustment of the adjusting plate g in the manner hereinbefore described, whereby the rate of movement of the measuring screw on reverse operation from the meter is altered in the manner hereinbefore described.

45 As illustrated in Figures 1 and 7 of the drawings the lower end of the spindle r^1 may be mounted within a transverse slot in the lower bearing plate d^{31} formed integral with the supporting frame member d^3 and a 50 leaf spring w may be secured to the adjacent longitudinal member of the supporting frame d^3 , so that its free end applies a certain amount of pressure at the lower end of the spindle r^1 to facilitate the accommodation 55 of the worm s to the worm wheel q on the change of gear and to maintain the worm in 60 engagement.

65 It will be understood that any other mechanical means than hereinbefore described may be employed to bring the stop plate or

the equivalent in position upon the adjustment of the coin holder, but that the independent adjustment of the stop plate or the equivalent and of the coin holder or the adjusting plate is within the scope of the invention.

70 Thus the method of mounting the adjusting plate on the coin holder may vary widely in detail, while providing in a simple and convenient way for the movement of the adjusting plate relatively to the pawl plate e . Thus again instead of providing the stop plate as a lever it may be provided as an extension of or addition to the adjusting plate g and be adapted to come into its effective 75 position on the adjusting plate being moved. Similarly when providing the stop plate as a lever it may be otherwise connected or be operable from the adjusting plate. Again any other alternative gearing may be employed 80 operable in the respective positions of the sleeve m or its equivalent, on actuation in the manner hereinbefore described.

85 It will furthermore be understood that the invention may be applied for use with more than two coins in which event more than one stop plate or its equivalent may be provided, with a corresponding number of gear changes in the manner hereinbefore described.

90 It will furthermore be understood that the mechanism as hereinbefore described may be incorporated within the meter casing in known manner and protected against unauthorized access to it.

95 We claim:

1. In prepayment mechanism for gas and similar meters adapted for operation by coins of more than one value, the provision of a coin holder casing, a coin holder for reception within said casing, an element movable relatively to and carried by said coin holder whereby the coin space is adjusted according to the size of the coin in use, a measuring element for operation by said coin holder, change gear connected to said measuring elements, for varying the gear ratio of the mechanism according to the value of the coin in use, an axially movable part adapted in its axial movement to adjust said change gear, and a stop member upon said coin holder movable into and out of line with the axially movable part in dependence upon the variation of the coin space the said axial movement being effected by said stop member on introduction of the coin holder into the casing.

105 2. In prepayment mechanism for gas and similar meters adapted for operation by coins of more than one value, the provision of a coin holder casing, a coin holder adapted for reception within said casing, an element movable relatively to and carried by said coin holder whereby the coin space is adjusted according to the size of the coin used,

- a measuring element for operation by said coin holder, a member mounted in said coin holder and adjustable in position according to the adjustment of the coin space, and
 5 means operated by said member in one of its positions on introduction of the coin holder into the coin holder casing to cause a change in gear ratio of the mechanism according to the value of the coin used.
- 10 3. In prepayment mechanism for gas and similar meters, a coin holder casing, a coin holder adapted for reception within said coin holder casing, an adjustable part in said coin holder for varying the coin space according
 15 to the size of the coin intended to be used, a measuring element for operation by said coin holder, a stop member of adjustable position moved by said adjustable part of the coin holder, a change gear for variation of the
 20 gear ratio of the mechanism, an axially movable member adapted in its axial movement to effect adjustment of the change gear according to the value of the coin intended to be used, said axially movable part being op-
 25 erated from the said stop member upon the coin holder being set into position within its casing.
4. In prepayment mechanism for gas and similar meters adapted for operation by coins
 30 of more than one value, a coin holder casing, a coin holder for reception within said casing, means upon said coin holder for adjustment of the coin space according to the value of the coin intended to be used, a measuring
 35 element for operation by said coin holder, a change gear for effecting variation in the gear ratio of the mechanism according to the value of the coin intended to be used, an axially movable spindle adapted by its axial move-
 40 ment to effect adjustment of the change gear, and a stop member upon the coin holder which is adjustable in position in correspondence with the adjustment of the coin space, said stop member serving on introduction of
 45 the coin holder into the coin holder casing to cause axial movement of the axially movable spindle according as the coin space of the coin holder may have been adjusted for the reception of a coin of a value other than
 50 the normal value.
5. In prepayment mechanism as specified in claim 4, a coin holder having a coin space which is adjustable to receive a coin of a value other than that which it would receive
 55 before adjustment, and a stop member upon said coin holder movable in correspondence with the adjustment of the coin space into a position in which it may actuate the axially movable spindle to cause the variation in the
 60 gear ratio of the mechanism to correspond to the value of the coin to be used on insertion of the coin holder into the coin holder casing.
6. Prepayment mechanism for gas and similar meters, comprising a coin holder casing,
 65 a rotatable coin holder for reception within
- said casing, a toothed measuring wheel also contained within said coin holder casing, a sliding pawl plate within said coin holder to operate said measuring wheel, an adjusting plate upon said sliding pawl plate, the said adjusting plate being adjustable lengthwise of the coin holder to be movably set upon the sliding pawl plate to vary the depth of the coin space for the accommodation of coins of different values and to be movable with the sliding pawl plate in the operation of the coin holder, a stop member carried by said coin holder and movable in correspondence with said adjusting plate, a change gear for varying the ratio of the mechanism according to the value of the coin intended to be used,
 70 and an axially movable spindle for effecting the adjustment of the change gear, the said stop member serving on introduction of the coin holder into the coin holder casing to effect axial movement of the axially movable spindle according as the stop member is adjusted in a position other than the normal position.
7. In prepayment mechanism for gas and similar meters as specified in claim 6, in which the axially movable spindle is co-axial with and extends into the coin holder casing, and a stop member comprising a pivoted stop plate which on adjustment is moved from an inoperative position to a position in which it engages and moves the axially movable spindle on introduction of the coin holder into the coin holder casing.
8. In prepayment mechanism for gas and similar meters as specified in claim 6, in which said change gear comprises a measuring screw, an axially immovable sleeve having an internal thread in which the said measuring screw is adapted to engage, a sliding sleeve upon the said axially immovable sleeve, a gear wheel mounted upon the said sliding sleeve and gear elements with which the said gear wheel may engage in succession on axial movement of the said sleeve, the said sleeve being moved by the axially movable spindle, and a spring to oppose said movement.
9. In prepayment mechanism for gas and similar meters adapted for operation by coins of more than one value, the provision of a coin holder casing, a coin holder for reception within said casing, an element movable relatively to and carried by said coin holder whereby the coin space is adjusted according to the size of the coin used, a measuring element for operation by said coin holder, change gear by which variation of the gear ratio of the mechanism may be effected according to the value of the coin intended to be used, said change gear comprising co-axial right and left hand worms relatively non-rotatable, a worm wheel in constant engagement with one of said worms, a worm co-axial with and relatively non-rotatable with respect to said worm wheel, and a slidably worm wheel

adapted in one position to engage the second of the co-axial worms, and in another position to engage the worm co-axial with the first worm wheel, an axially movable part adapted 5 in its axial movement to move said slideable worm wheel, and a stop member upon said coin holder movable into and out of line with the axially movable part in dependence upon the variation of the coin space the said axial 10 movement being effected by said stop member on introduction of the coin holder into the casing.

10. In prepayment mechanism for gas and similar meters, the provision of a coin holder 15 casing with a coin discharge opening, a coin holder for reception and movement within said casing, a measuring element actuated by said coin holder, gearing through which said measuring element is actuated reversely from 20 the meter mechanism, a shutter movable about the exterior of the coin holder casing on an axis parallel with that of the coin holder to obturate the said coin discharge opening, a cam element controlling the position of 25 said shutter and operated from said measuring element, said shutter closing said coin discharge opening on prepayment of a maximum volume of the commodity to be measured.

11. In prepayment mechanism for gas and 30 similar meters as specified in claim 10, the

provision of a scale indicating the quantity of commodity for which prepayment has been made, and a pointer co-operating with said scale and actuated from and integral with said shutter.

12. In prepayment mechanism for gas and similar meters adapted for operation by coins of more than one value, the provision of a coin holder casing, a coin holder for reception within said casing, a movable element in said coin holder whereby the coin space is adapted to receive the particular size of coins used, a measuring element actuated by said coin holder, change gear by which variation in the gear ratio of the mechanism may be effected according to the value of the coin intended to be used, an axially movable part adapted in its axial movement to adjust said change gear, and a stop member upon said coin holder movable into and out of line with the axially movable part according to the size of the coin space the said axial movement being effected by said stop member on introduction of the coin holder into the casing where said coin holder is adapted for the reception of a coin of a size other than that represented by the normal setting of the change gear.
